CLAIM

The ornamental design for a shoe as shown and described.

DESCRIPTION

FIG. 1 is a rear bottom perspective view of a shoe showing my new design;

FIG. 2 is a bottom view thereof; and,

FIG. 3 is an opposite side rear bottom perspective view thereof.

The broken lines immediately adjacent to and surrounding the shaded area define the peripheral bounds of the claimed

(Continued)

design and form no part thereof. The broken lines depicting the remainder of the shoe form no part of the claimed design.
